UNITED STATES PATENT OFFICE.

FRANK ZAHORIK, OF RACINE, WISCONSIN.

DIAL TEST-INDICATOR.

1,152,686.

Specification of Letters Patent. Patented Sept. 7, 1915.

Application filed July 23, 1914. Serial No. 852,742.

To all whom it may concern:

Be it known that I, FRANK ZAHORIK, subject of Austria, residing at Racine, in the county of Racine, State of Wisconsin, have invented certain new and useful Improvements in Dial Test-Indicators; and I do hereby declare the following to be a full, clear, and exact description of the invention, such as will enable others skilled in the art to which it appertains to make and use the same:

This invention relates to measuring instruments and has special reference to a dial test indicator.

The principal object of the invention is to improve and simplify the construction of devices of this character.

A second object of the invention is to provide, in a device of this character means for preventing back lash in the gearing used.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1, is a face view of the device constructed in accordance with this invention. Fig. 2, is a section on the line 2—2 of Fig. 1. Fig. 3, is a view similar to Fig. 1 but with the dial removed and the casing broken away to show the operating parts. Fig. 4 is a section on the line 4—4 of Fig. 3.

In carrying out the objects of this invention there is provided a case 10 having mounted thereon a ring 11 which is so arranged as to rotate on the casing. This ring 11 carries a dial 12 provided with graduations 13, each of these graduations preferably indicating one one-thousandth of an inch. The usual watch crystal 14 covers the dial and protects the parts from dust.

Fixed to the bottom of the casing is a bearing 15 for the staff 16 of a pinion 17. This staff extends through the dial and carries on its outer end a hand or pointer 18 which traverses the dial as the pinion is rotated. Extending from the side of the casing is a tubular projection 19 wherein is mounted a spindle 20, the spindle having a head 21 provided with a beveled end 22. One side of the head is flattened at 23 and bears

against the bottom of the casing to prevent the rotation of the spindle and this holds the beveled face in proper position. Mounted within the casing is a staff 24 carrying a lever arm 25 provided with a head 26 which engages the beveled end of the head 22. This staff 24 carries a second arm 27 supporting at its end a segmental gear 28 which meshes with the pinion 17. A short arm 29 also projects from the staff 24 and is connected by a spring 30 to a pin 31 within the casing.

Now when the spindle 20 is forced inward this will cause movement of the gear 28 and consequently rotation of the pinion 17 so that the hand 18 will traverse the dial. Owing to the beveled face 22 the movement of the hand will correspond correctly to the inward movement of the spindle 20 with the exception of the lost motion between the gear and pinion, the bevel being properly arranged to this end. The spring 30 will, of course, return the parts when pressure on the spindle 20 is relaxed.

In order to prevent the lost motion above referred to there is pivoted within the casing a second lever 32 carrying at its end a segmental gear 33 which meshes with the pinion 17 on the side opposite the gear 28. A second spring 34 is employed to hold the lever 32 in such a position as to cause constant engagement of the teeth on the gear 33 with the teeth of the pinion 17. In order to provide for the lever 32 the casing is provided with an extension 35 and this extension carries at one end a bearing 36 for a spindle 37, the latter being arranged at right angles to the spindle 20. This spindle is shouldered within the casing and the rounded end 38 of the lever 32 rests on this shoulder. Both spindles are provided with threaded sockets for the reception of the threaded stems 39 of contact points 40 the latter being of any desired shape. Now, if either of the spindles be forced in the spring controlled remaining spindle will be tensioned so that there will be no lost motion or back lash in the gearing.

In use the dial can be rotated to bring the zero point beneath the end of the hand whenever desired the measurements being started from such positions. Furthermore a suitable ear 41 is provided on the back of the casing for attachment of the device to any support.

There has thus been provided a simple

and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such 10 as come properly within the scope claimed.

By providing the head 21 with the beveled end 22 it is obvious that the head 26 can slide freely when the spindle 20 is operated.

Having thus described the invention, what 15 is claimed as new is:

In a measuring instrument of the kind described, a hand carrying staff, a pinion on said staff, gears meshing with said pinion

Copies of this patent may be obtained for five cents each, by addressing the "Commissioner of Patents, Washington, D. C."

on opposite sides thereof, springs urging 20 said gears in opposite directions, reciprocal spindles, and operative connections between respective spindles and gears one of said connections including a bell-crank lever having one arm connected to the related gear, the inner end of the adjacent spindle 25 being provided with a beveled face arranged to engage the other arm of the bell-crank to rock the same when said spindle is reciprocated.

In testimony whereof I affix my signature, 30 in the presence of two witnesses.

FRANK ZAHORIK.
